(57) CLAIM

The ornamental design for a tube connector, as shown and described.

DESCRIPTION

FIG. 1 is a isometric view of my new tube connector showing the new design;

FIG. 2 is a exploded view of FIG. 1 with a small portion cut away for clarity;

FIG. 3 is a enlarged front end elevation view of FIG. 1;

FIG. 4 is a enlarged rear end elevation view of FIG. 1;

FIG. 5 is a enlarged right side elevation view of FIG. 1 the left side elevation view being a mirror image thereof;

FIG. 6 is a enlarged top end view of FIG. 1; and,

FIG. 7 is a enlarged bottom end view of FIG. 1.

Broken lines throughout the views show the environment in which the design is used and form no part of the claimed design.
